CLAIM

The ornamental design for a double ended lamp reflector kit, as shown and described.

DESCRIPTION

FIG. 1 is a perspective view of a first embodiment of a double ended lamp reflector kit, as viewed from below, showing my new design;

FIG. 2 is a left side view of the kit shown in FIG. 1;

FIG. 3 is a right side view of the kit shown in FIG. 1;

FIG. 4 is a front elevation view of the kit shown in FIG. 1;

FIG. 5 is a rear elevation view of the kit shown in FIG. 1;

FIG. 6 is a top plan view of the kit shown in FIG. 1;

FIG. 7 is a bottom plan view of the kit shown in FIG. 1;

FIG. 8 is a perspective view of a second embodiment of a double ended lamp reflector kit, as viewed from below, showing my new design;

FIG. 9 is a left side view of the kit shown in FIG. 8;

FIG. 10 is a right side view of the kit shown in FIG. 8;

FIG. 11 is a front elevation view of the kit shown in FIG. 8;

FIG. 12 is a rear elevation view of the kit shown in FIG. 8;

FIG. 13 is a top plan view of the kit shown in FIG. 8;

FIG. 14 is a bottom plan view of the kit shown in FIG. 8;

FIG. 15 is a perspective view of a third embodiment of a double ended lamp reflector kit, as viewed from below, showing my new design;

FIG. 16 is a left side view of the kit shown in FIG. 15;

FIG. 17 is a right side view of the kit shown in FIG. 15;

FIG. 18 is a front elevation view of the kit shown in FIG. 15;

FIG. 19 is a rear elevation view of the kit shown in FIG. 15;

FIG. 20 is a top plan view of the kit shown in FIG. 15; and,

FIG. 21 is a bottom plan view of the kit shown in FIG. 15.

The broken lines in the drawings illustrate portions of the double ended lamp reflector kit which form no part of the claimed design.

1 Claim, 9 Drawing Sheets

Related U.S. Application Data

a division of application No. 29/562,651, filed on Apr. 27, 2016, now Pat. No. Des. 847,394, which is a division of application No. 29/481,879, filed on Feb. 11, 2014, now Pat. No. Des. 758,646.
